UNITED STATES PATENT OFFICE

2,166,886

CARRIER IRON AND BRAKE FULCRUM

Ray G. Aurien, Chicago, Ill., assignor to American Steel Foundries, Chicago, Ill., a corporation of New Jersey

Application September 4, 1937, Serial No. 162,410

14 Claims. (Cl. 188—205)

My invention is directed to a novel form of steel casting designed for use as a railway car underframe reinforcing member, a carrier iron and a fulcrum means for brakes associated with said car.

In certain types of railway cars it is desirable to make such a connection between the car body and the brake rigging, which is normally supported on the car truck, as will prevent a resultant of forces tending to move the truck away from the center pin connection with the car body. One such type of truck and brake arrangement is described in detail in the co-pending Hedcock application bearing Serial No. 72,894 and filed in the United States Patent Office April 6, 1936, wherein fulcrum connections are provided on opposite sides of the bolster in the same plane thereof in order to prevent a tendency to rotate the bolster and, at the same time, a fulcrum point for the brake rigging as a whole is provided by a connection to the underframe of the car body in the vicinity of the coupler carrier iron. In the construction shown in the Hedcock application above referred to, as well as in the embodiment shown herein for illustrative purposes, a lever forming a portion of the brake system is fulcrumed at a point intermediate its ends at a convenient point along the center sill forming a part of the car body underframe. Inasmuch as such an arrangement, where required, results in the application of unusual stresses to the center sill, I have designed a special form of carrier iron, fulcrum bracket and reinforcing casting which may be made use of in such an arrangement of railway brake rigging.

An object of my invention is to design a novel form of center sill brace, carrier iron and brake fulcrum which will accommodate such constructions as are above referred to.

A more specific object is to design a steel casting which will permit the fulcruming from the car body of the brake rigging associated with the railway car truck while, at the same time, furnishing reinforcement of the center sill structure to compensate for the additional stresses involved.

With these and various other objects in view, the invention may consist of certain novel features of construction and operation as will be more fully described and particularly pointed out in the specification, drawing and claims appended hereto.

In the drawing which illustrates an embodiment of the device:

Figure 1 is a top plan view of my novel form of center sill reinforcement and brake fulcrum bracket;

Figure 2 is a front elevation thereof, and Figure 3 is an end elevation;

Figure 4 is a fragmentary transverse sectional view through a railway car structure showing a portion of the underframe and a portion of the car truck with my novel reinforcing casting and fulcrum bracket incorporated therein; and

Figure 5 is a fragmentary plan view of the car and truck structure shown in Figure 4.

Describing in more detail the form of my novel casting generally indicated at 1, it will be seen that the casting comprises a plate-like body portion 2 elevated at its opposite ends as at 4 and 6 and reinforced throughout the major portion of its length by the vertically disposed longitudinal flange 8 which merges at one end into the elevated portion 4 and at the opposite end into the brake lever fulcrum structure generally indicated at 10. The opposite ends of the casting are provided with the rivet holes 12, 12 forming a means of connection to the spaced center sills 14, 14 (Figure 4). Reinforcing the juncture of the brake lever fulcrum 10 and the elevated end portion 6 is the vertical flange 16. The upper surface of the plate 2 along the center portion thereof as at 18, 18 affords a seat for the yoke normally surrounding the draft gear. In the vicinity of the bracket 10 the casting is widened as at 20 in order to form the transverse slot 22 of a width suitable to accommodate the central portion of the brake lever 24 (Figure 5). The flat top and bottom faces of the slot 22 designated respectively 26 and 28 closely confine the brake lever 24 and prevent tilting thereof. The lever 24 is secured within the slot by means of the pin 30 which is received in the aligned openings 32 and 34 formed respectively in the bottom and top walls of said slot, said pin 30 being retained in position by the bolt and nut assembly 36 which is secured in the aligned openings 38 and 40 formed respectively on the ears 42 and 44 at the bottom of the fulcrum structure.

In Figures 4 and 5 I have shown a typical application of my novel form of casting to the underframe of a car body. It will be apparent that my novel casting is secured to the center sills at the normal position of the carrier iron, between the car end and the bolster 15. The casting 1 is secured to the under surface of the spaced center sills 14, 14 as by means of the rivets 46, 46, the depressed central portion of its upper surface forming a seat 18 for the yoke 55

normally associated with the draft gear, said casting having adjacent one end thereof the novel form of brake lever fulcrum 10 as above described. The brake lever 24 is received in the 5 slot 22 as most clearly seen in Figure 4 and secured therein at a point intermediate its ends by the pin 30.

Other portions of the brake rigging may normally be connected to the opposite ends of the 10 brake lever 24 as at 48 and 50 as shown for example in the above described Hedcock application Serial No. 72,894.

It will thus be seen that in my novel form of composite casting I have provided at a critical 15 point a substantial reinforcement for the spaced center sills of the car body while, at the same time, furnishing an adequate carrier iron and a satisfactory form of fulcrum connection for brakes normally associated with the truck upon 20 which the car body is supported.

It is to be understood that I do not wish to be limited by the exact embodiment of the device shown, which is merely by way of illustration and not limitation, as various and other forms 25 of the device will of course be apparent to those skilled in the art without departing from the spirit of the invention or the scope of the claims.

I claim:

1. In a railway car a car body including spaced 30 center sills, a supporting truck for said car body, a reinforcing member connecting said spaced center sills, said member comprising a depressed center portion forming a seat for a draft gear yoke and an integrally formed brake lever ful-

35 crum, and a brake lever secured in said fulcrum at a point intermediate the ends of said lever and adapted to serve as a means of connection between said car body and brake rigging associated with said car truck.

2. In a railway car a car body including spaced 40 center sills, a truck supporting said car body, a cast steel reinforcing member connecting said spaced sills and forming carrying means for a draft gear yoke, a brake lever fulcrum integrally formed with said member, and a brake lever 45 secured in said fulcrum and adapted to form a means of connection between said car body and brake rigging associated with said car truck.

3. In a railway car a car body having spaced 50 center sills, a truck supporting said car body, a cast reinforcing member joining said spaced sills and serving as a carrier iron, a brake lever fulcrum integrally formed with said member, and a brake lever secured in said fulcrum at a point 55 intermediate the ends of said lever and adapted to serve as a means of connection between said car body and brake rigging associated with said car truck.

4. In a railway car a car body having spaced 60 center sills, a truck supporting said car body, a cast steel reinforcing member for said spaced sills, a longitudinal reinforcing flange and a bracket comprising spaced walls defining an opening for a brake lever, and a brake lever secured in said opening and adapted to serve as 65 a means of connection between said car body and brake rigging associated with said car truck.

5. In a railway car a car body including spaced center sills, a supporting truck for said car body, a cast steel reinforcing member connecting said sills, said member having a seat for a draft gear yoke and an integrally formed brake lever fulcrum, and a brake lever positioned in said fulcrum and adapted to serve as a means of connection between said car body and brake rigging associated with said car truck. 5

6. In a railway car spaced center sills, a cast 10 steel reinforcing member joining said sills, said member comprising a depressed central portion forming a seat for a draft gear yoke and an integrally formed brake lever fulcrum, said fulcrum comprising top and bottom walls forming 15 a slot therebetween, and aligned openings in said walls for the reception of brake lever securing means.

7. A cast steel reinforcing member for a railway car center sill comprising a depressed plate 20 portion serving as a seat for a draft gear yoke, longitudinally arranged reinforcing flanges, and an integrally formed bracket on said member comprising top and bottom walls and end walls defining a slot for the reception of a brake lever. 25

8. In a railway car a car body having spaced center sills, a truck supporting said car body, a cast steel reinforcing member for said spaced sills, said member comprising a seat for a draft gear yoke, and a bracket having spaced walls 30 defining an opening for the reception of a brake lever, certain of said walls having aligned openings for the reception of securing means for said lever.

9. A cast steel reinforcing member for a rail- 35 way car center sill comprising a depressed plate portion serving as a seat for a draft gear yoke, longitudinally arranged reinforcing flanges, and an integrally formed bracket comprising top and bottom walls defining a brake lever slot, and 40 aligned openings in said walls for the reception of securing means for a brake lever.

10. In a railway car spaced center sills, a cast 45 steel reinforcing member joining said sills, said member comprising a depressed central portion forming a seat for a draft gear yoke, and an integrally formed brake lever fulcrum.

11. A cast steel reinforcing member for a rail- 50 way car center sill comprising a depressed plate portion serving as a seat for a draft gear yoke, longitudinally arranged reinforcing flanges, and an integrally formed brake beam fulcrum.

12. In a railway car center sills, a cast steel 55 reinforcing member for said sills, a brake lever fulcrum integrally formed with said member, said member having longitudinally arranged reinforcing flanges.

13. In a railway car center sills, and a cast 60 steel reinforcing member for said sills, said member having a yoke seat and an integrally formed brake lever fulcrum.

14. In a railway car a cast steel center sill reinforcing member comprising a seat for a draft gear yoke, and an integrally formed brake lever fulcrum. 65
